VENT LOCK FOR SLIDING DOORS

Donald B. Hawkins, Danville, Calif.
(2233A Washington Ave., San Leandro, Calif. 94526)

Filed May 19, 1969, Ser. No. 17,216

Term of patent 14 years

Int. Cl. D8—03

U.S. Cl. D8—109

FIG. 1

FIG. 2

FIG. 3

FIG. 4

FIG. 5

FIG. 6

FIG. 7

FIG. 8

FIG. 5

FIG. 1 is a perspective view of a vent lock for sliding doors showing my new design;

FIG. 2 is a side elevational view;

FIG. 3 is another side elevational view;

FIG. 4 is a top plan view; and

FIGS. 5 through 8 are views corresponding to FIGS. 1 through 4 of a modified form of design.

I claim:

The ornamental design for a vent lock for sliding doors, substantially as shown and described.
